BUILDING CONSTRUCTION

Joseph Di Stasio, Newark, N. J.

Application January 8, 1934, Serial No. 705,754.

5 Claims. (Cl. 72—1)

This invention relates to new and useful improvements in building structures of the monolithic type, and while with modification, it may be adapted to use in connection with buildings of the larger type, it particularly lends itself to the erection of buildings of the smaller type such as dwellings, multiple family houses, and the like.

The buildings referred to are of the monolithic type and are, when completed, suitably reinforced to withstand the strains and stresses to which they may be subjected in actual use.

An object of the invention is to provide a novel fireproof construction and method of erection which will materially reduce the material and labor necessary in the erection of such structures and thereby materially reduce the cost of the finished building.

In actual practice, I follow to a certain extent the ordinary method of construction of monolithic buildings in that I employ a metal framework about which the monolithic structure is formed. The present invention differs, however, in many respects from the methods and constructions generally employed and particularly it differs from common practices in that the metal framework which I employ, forms the major reinforcement of the finished structure.

A feature of the invention resides in the use of a relatively thin light metal in the construction of the metal framework, the metal which I employ being of such character that in buildings of the afore-mentioned type as ordinarily constructed, its use would be prohibitive.

A further feature of the invention resides in a novel construction of metal framework which, although it is a permanent structure, serves the purposes of forms for the molding of the monolithic structure, and thereby eliminates the labor incident to the tearing down of the forms after the completion of the building as well as the loss incident to the waste of material employed in erecting forms.

Still a further feature of the invention resides in a novel construction of metal framework whereby reinforcing elements, other than the metal framework itself and its component parts may be entirely dispensed with.

Other features of the invention relate to certain novel and improved constructions, arrangements and combinations of parts hereinafter described, and particularly pointed out in the claims, the advantages of which will be readily understood and appreciated by those skilled in the art.

55 The invention will be understood from the ac-

companying drawings illustrating the invention in its preferred form and the following detailed description of the constructions therein shown.

In the drawings,

Figure 1 is a fragmentary sectional perspective view of a section or portion of a building constructed in accordance with the present invention.

Figure 2 is a horizontal sectional view partly broken away and taken substantially on the line 10 2—2 of Figure 1.

Figure 3 is a vertical sectional view taken substantially on the line 3—3 of Figure 2.

Figure 4 is a detail vertical sectional view taken longitudinally of one of the beams and 15 transversely of the adjacent column.

Figure 5 is a transverse sectional view taken on the line 5—5 of Figure 1.

Figure 6 is a detail perspective view of one of the elements employed in the joining of a beam 20 member of the metal framework to one of the column members thereof.

Figure 7 is a detail perspective view of a fastening means employed in securing a wall structure to the monolithic structure.

Figure 8 is a top plan view of a partition column member, showing the several partition beam members extending therefrom and the means employed to attach them thereto.

Figure 9 is a detail sectional view of a slightly 30 modified form of the invention, and;

Figure 10 is a detail perspective view of the construction illustrated in Figure 9.

In the present embodiment of the invention, the metal framework is designated broadly by the 35 reference character A. This metal framework A consists of vertical columns B, girder or spandrel sections C and beam sections D.

The several elements which go to make up the framework are constructed of relatively thin light 40 metal and are so constructed and arranged as to receive and contain concrete or other plastic compositions from which the building is to be constructed. Another important feature of construction of this framework consists of so shaping 45 the elements thereof that in addition to providing molds for the shaping of the monolithic structure, the several elements thereof become a permanent part of the monolithic structure and provide the reinforcing elements of the said monolithic structure.

By reference to the drawings, it will be noted that there are two types of column elements in the frame structure. In Figure 1, there is shown 55 a construction which particularly lends itself to

outside wall columns, while in Figure 8, there is shown a structure which is particularly adapted for use in connection with partition wall columns.

Referring to Figure 1, the column members E 5 consist of relatively thin light sheet metal members of substantially channel form. The column elements are designated 20, and in this type of column the elements have side walls 21, and an open side 22. The open side is defined by flanges 23, which are formed by bending the metal, as indicated at 24 in said figure. The wall 25, of each of this type of column member is provided with an inwardly disposed flange 26, which construction provides a groove or the like 27, which extends 10 throughout the length of the inner face of these column elements. These grooves provide means for attaching wall finishes in that they receive fastenings 28, as best illustrated in Figure 5 of the drawings, which fastenings may be driven 15 through a wall board or similar facing material designated 29. In the present instance, the fastenings 28, have been illustrated as nails or similar driven headed devices. In addition to forming means for frictionally retaining the fastening 20 elements 28, the inwardly disposed flange 26, serves as a reinforcing element for the finished concrete structure. In carrying out the invention, it is to be understood that the column elements are filled with concrete or similar plastic 25 material which completely embraces or encloses the flanges 26, and embeds the latter when the plastic material sets. Thus it will be apparent that the inwardly disposed flange 26, provides a 30 reinforcing element which extends throughout the length of the column.

The girder or spandrel sections are herein illustrated as formed from two channel members arranged in back to back relation, these channel members being designated 30 and 31. The edges 35 of the side walls of the channel member 30 are formed with outwardly disposed flanges 32, while the edges of the side walls of the upper member 31, are formed with inwardly disposed flanges 33.

The beam elements of this framework are of substantially the same construction as the elements which form the columns, and by reference to Figure 1, it will be noted that these beam elements which are designated 34, have an inwardly disposed flange 35 in their bottom wall. The side walls are folded inwardly as at 36, and downwardly as at 37, to provide flanges 38, which are arranged within the confines of these several elements. When the plastic material is filled into the several girder and beam elements, it will be noted that the flanges 35, and 38, of the beam members D will be embedded in the plastic material in such a manner that these flanges will provide reinforcing elements for the beams formed thereby, while the inwardly disposed flanges of the girder sections will likewise be embedded to form reinforcing elements for the girders.

These several elements, that is, the girder and the beam elements are secured to the column elements in the following manner. Referring to Figure 4 of the drawings, it will be noted that each column element which serves as a girder or beam, supporting member is provided with an outwardly struck supporting lip or lug 38. The ends of the girder and beam sections of the metallic frame are closed, and that end of each which abuts a column element is cut out as at 39, to provide a downwardly extending lug or flange 40, which is adapted to engage behind the supporting lip or lug 38, as illustrated. At the

proper location, the column element is provided with an opening 41, and the closed end of the beam element which abuts the column element is provided with an opening 42. When the column element is in position, these openings 41 and 42 are in registration with each other, and in this position are capable of receiving a locking element 43, of the type illustrated in Figure 6, and consisting of a relatively narrow strip of metal having a right angular extension 44, at 10 one end, and adjacent the right angular extension, the main body of this member is cut out as at 45, and bent as at 46, to provide an extending lug or shoulder 47. When the beam or girder and column members have been assembled as described, this locking member 43 is passed through the registering openings 41, and 15 42, until the lug or projection 47, engages the column elements as indicated at 48, in said Figure 4. This throws the opening 45, in the locking member to position where it will receive a wedge 49, which when driven home clamps the abutting faces of the column element and the closed element of the girder or beam element between itself and the projecting lug or shoulder 20 47. This member may next be bent downwardly as at 50, to provide a shear or reinforcing element 51, which extends into the girder or beam element as illustrated in Figure 4. Inasmuch as the girder and beam elements are secured to 25 the column elements in the manner just described, it will be unnecessary to give a further description of this form of the invention except to say, as illustrated in Figure 2, two such locking elements may be employed if desired. 30

As best illustrated in Figure 1, floor slabs 55 rest upon the beam elements D and spandrel or girder elements C. These several floor slabs are of ordinary construction and employ reinforcing elements 56, which, when the floor slabs are 40 placed in position, as just described, are bent downwardly into the girder and beam elements as illustrated at 59 in Figure 1, and 58 in Figure 5, so that it will be embedded in the plastic material which forms the monolithic structure. 45 The several floor slabs having been positioned, the plastic material which is herein designated by the reference numeral 60, is poured or otherwise placed into the hollow column, girder and beam sections, to level with the floor slabs 55, 50 thus embedding the extended reinforcements of the floor slab to anchor or secure the floor slabs in position, thereby obtaining a monolithic T-beam type construction. The reference numeral 55 designates outer wall facing elements, and these are likewise reinforced by suitable reinforcing elements 66 which are adapted to be bent in such a manner as to lie within the confines of the column elements in such a manner that when the column elements are filled with plastic material, these reinforcing elements 66, will be embedded therein to hold the outer wall facing elements 65, in position. In the illustrated embodiment of the invention, 67 designates a finish facing which may be stucco or any other 60 desired type.

The wall facing elements 65, are maintained in position during the forming of the monolithic structure by suitable fastenings which consist of relatively flat members 70, embedded in the 70 wall facing elements and cut out as at 71, for the reception of wedges 72. However, before the wedges 72, are placed in position, the projecting portions of the members 70, are engaged with openings 73, in clip-like members 74, each of 75

which has a right angular end 75, and a projecting lug 76. As best illustrated in Figure 2 of the drawings, these clip-like members pass through openings 78, in the side walls of the column elements and engage the inwardly turned portions 79, thereof, as illustrated at 80, in said Figure 2. If, now, the wedges 72, be positioned, it will be seen that through the medium of the clip-like members 74, the wall facing elements 65, will be secured to the column elements, and further, that after the monolithic structure is formed, these clip-like members will be anchored to the mold body which forms the columns of the finished structure.

15 In Figure 8, I have shown a form of the invention in which the several beam elements are adapted to partition carrying columns. In Figure 8, these columns are designated 80', the beaming element being designated 81. The fastening elements which in this figure are designated 82, are continuous in that they extend clear across the column element. They are each provided with a lug 83, which is adapted to engage the column element and each has three openings for the reception of wedges 84, which act in a manner similar to the wedge 49, heretofore described. The openings in the column elements through which these members pass may be arranged in groups at different levels or the members themselves 30 may be slightly bent to cross one another within the column as shown in said Figure 8.

In some instances it may be desirable to add strength to the finished structure and in the modified form of the invention, as illustrated in Figures 9 and 10, this added strength is provided by means of a member 90, which is adapted to pass through registered openings 91, in the side wall of the column elements and the adjacent end wall of the girder or beaming elements. 40 This member 90, is provided with a notch 92, and with a projecting lug 93. The openings 91, heretofore described, are of inverted T-shape and as the reinforcing element 90, is passed into the openings 91, the projection or lug 93, will engage the wall of the column element to limit movement of the reinforcing element 90. When the projection or lug 93, engages the column element, the notch 92, will register with the upper edge of the slot 91, and if the wedge 95, now be inserted into the portion 96, of the slot 91, the reinforcing element 90, will be forced upwardly so that its notch 92, receives the end edge 94, of the slot 91, to lock the reinforcing element 90, against movement. When the plastic material is filled 55 into the column, girder and beam elements, the reinforcing element 90, will be embedded, thus serving its purpose.

From the foregoing it will be apparent that the present invention provides a new and novel construction and arrangement of parts which particularly lends itself to the construction of relatively light buildings, such as dwelling houses, garages and similar structures. It will also be noted that while the metallic framework is in 60 itself incapable of use in the ordinary manner of building, it is of sufficient strength to provide for its erection and also to serve as reinforcing elements for the finished monolithic structure in such a manner that reinforcing elements as 65 they are commonly known and employed such as bolts, rivets, bars, beams, rods and the like may be dispensed with, thus merely reducing the material and labor necessary in the erection of a building and thereby materially decreasing the 70 finished cost thereof.

While in the present embodiment the invention has been illustrated in its preferred forms, it is to be understood that it is not to be limited to the specific construction herein shown, and that it may be practiced in other forms which rightfully fall within the scope of the appended claims.

Having thus described the invention, what is claimed as new and what it is desired to secure by Letters Patent of the United States, is:

1. In a structure of the type described, a hollow metallic column member adapted to receive plastic molding material, said column being provided with openings in its side walls, supporting projections struck from the side walls of said hollow columns, hollow metallic beam members having closed ends provided with openings adapted for registration with the openings in the columns when the beam members are in position thereon, means projecting from the sides of said column members for supporting the beam members in position, means passing through the registered openings in columns and the closed ends of the beam members for securing the beam members to the column members, said last mentioned means comprising strips of metal extending substantially into the column members and into the beam members for anchoring in the plastic material, a projection on each strip, an opening through each strip, and a wedge member through the opening of the strip to clamp the column member and the beam member between the wedge and the projection on the fastening means.

2. In a structure of the type described, a hollow metallic column member adapted to receive plastic molding material, said column being provided with openings in its side walls, supporting projections struck from the side walls of said hollow columns, hollow metallic beam members having closed ends provided with openings adapted for registration with the openings in the columns when the beam members are in position thereon, means projecting from the sides of said column members for supporting the beam members in position, means passing through the registered openings in columns and the closed ends of the beam members for securing the beam members to the column members, said last mentioned means comprising strips of metal extending into the column members and into the beam members, a projection on each strip, an opening through each strip, and a wedge member through the opening of the strip to clamp the column member and the beam member between the wedge and the projection on the fastening means with the ends of said fastening means projecting into the column and beam members and imbedded in the plastic material to form reinforcing elements for the finished monolithic structure.

3. In a structure of the type described, hollow metallic column members and hollow, metallic beam members adapted to receive a plastic molding material, said column members being provided with openings in its side walls, supporting projections for the beams struck from said side walls adjacent the openings, said beam members having partially closed ends, the open portion of the ends of the beams providing communication through certain of the openings in the columns for the plastic material whereby the material will intermingle when the members are supported in position, said ends of the beams having openings registering with the openings in

the columns, means passing through the registered openings in the columns and the ends of the beams for securing the beam members to the column members, said last named means comprising strips of metal extending substantially into the respective members for anchoring in the plastic material, a projection on each strip, said strip also having an opening, and a wedge member inserted through said opening of the strip to clamp the column and the beam between the wedge and the projection of the fastening means.

4. A building structure comprising a framework formed of a plurality of hollow, metallic elements, interengaging means on the elements for supporting the same in assembled position, a plastic molding composition poured into the elements, and a combined fastening and reinforcing member for securing a pair of the hollow elements together and including a projection struck from an intermediate portion of the member, a wedge insertable in the opening from

which the projection is struck, said projection and wedge cooperating to clamp the pair of hollow elements together and, said fastening member extending into the composition in each of the hollow elements a substantial distance to form a reinforcement for the composition.

5. A building structure comprising a framework formed of a plurality of hollow, metallic elements, interengaging means on the elements for supporting the same in assembled position, a plastic molding composition poured into the hollow elements, and a combined fastening and reinforcing member having means intermediate its ends for securing a pair of hollow elements together said means including a projection on the member and a wedge carried by the member cooperating with the projection to clamp the pair of hollow elements together, said member also having portions extending into the respective hollow elements and imbedded in the plastic composition to reinforce the same.

JOSEPH DI STASIO.
